CLAIM

The ornamental design for laser cutting machine, as shown and described.

DESCRIPTION

The patent or application file contains at least one drawing executed in color. Copies of this patent or patent application publication with color drawing(s) will be provided by the Office upon request and payment of the necessary fee.

1. Laser cutting machine

1.1 : Perspective

1.2 : Dimetric view (left side)

1.3 : Dimetric view (right side)

1.4 : Front

1.5 : Back

1.6 : Right

1.7 : Left

Laser cutting machine: 1.1 perspective view from below; 1.2 dimetric view from left side; 1.3 dimetric view from right side; 1.4 front view; 1.5 back view; 1.6 right side view; 1.7 left side view.

The broken lines showing features of the laser cutting machine are for the purpose of illustration only and form no part of the claimed design.
